ELECTRIC CONTROLLING DEVICE.

1,163,154.

Specification of Letters Patent.

Patented Dec. 7, 1915.

Application filed May 6, 1912. Serial No. 695,532.

To all whom it may concern:

Be it known that I, WINTHROP K. HOWE, a citizen of the United States, and a resident of the city of Rochester, in the county of 5 Monroe and State of New York, have invented a new and useful Electric Controlling Device, of which the following is a specification.

This invention relates to a device for controlling the movement, and indicating the completion of the movement, of a device remote therefrom.

The primary object of the invention is to increase the certainty and reliability of the 15 indication given at the controlling device, that the device remote therefrom has properly operated, and has assumed, and is in, a position in correspondence with the controlling device.

20 Other objects and advantages of the invention will become apparent to those skilled in the art as the description of the particular embodiment selected to illustrate applicant's invention, progresses.

25 In the drawing, consisting of a single figure, showing diagrammatically the circuits and apparatus selected by applicant, as exhibiting a particular physical embodiment of his idea of means; numeral 1 designates 30 a slide, having a latch 2 operated by the handle 3, for holding the slide in one of its moved positions. The slide contains a cam slot 4, by which a roller 5 is caused to move up and down, thereby causing an up and 35 down movement of a rod 6, which may actuate mechanical locking, such as is used in interlocking machines in railway signaling, and thus in a manner well understood by those skilled in the art, cause other slides,

40 similar to 1, to be locked in position or unlocked, so that they may be moved. The slide 1 may be moved manually in the direction of the arrow X, from the position shown, and may be returned from its moved 45 position to the position as shown, but its complete movement in either direction is governed by indication mechanism, which consists of shoulders 7, 8, 9, 10 and 11, the latch 13, the dog 14, the cam 15, the indication magnet 16, the rod 17 attached to armature 18, and the safety magnet 19. The function of said parts and the mode of operation thereof, is fully shown, described and claimed in the patent granted to John

D. Taylor, #752,127, dated February 16, 55 1904.

A rod 20 is connected to the slide 1 at one end, and at the other is attached to the conducting blocks 21 and 22, which, when in the position as shown, cause springs 23 60 and 24 and 25 and 26 respectively to be electrically connected. When the slide 1 is moved sufficiently in the direction of the arrow X, contact blocks 21 and 22 connect springs 27 and 28 and 29 and 30 respectively, so as to make an electrical connection there-between. The above mentioned contact blocks and springs, their function and mode of operation, is fully shown and described in the patent to John D. Taylor, 70 #752,127, above mentioned.

31 and 32 designate two electromagnets, so placed as to act upon the pivoted member 33, which in one of its positions forms a conducting path from contact 34 to contact 35, but when moved to a reverse position by means of electromagnet 31, forms a conducting path between contacts 34 and 36. The above described parts constitute 75 what are known as an indication selector and are fully shown, described and claimed in the patent granted to John D. Taylor, #832,175, dated October 2, 1906. Applicant's invention provides for additional coils 115 and 116 wound on electro-magnets 80 31 and 32 respectively for a purpose to be later explained.

The group of mechanism designated generally by A is equivalent in all respects with that shown, described and claimed in the 90 patent granted to John D. Taylor, #800,246, dated September 26th, 1905.

All of the devices, with the exception of coils 115 and 116, heretofore described are 95 thoroughly well known and understood by those skilled in the art of railway signaling and their mode of operation is generally as follows: When all of the parts are in the position as shown, known as the normal position, if slide 1 is moved in the direction of the arrow X, to what is called the reverse indication position, the motor whose commutator is designated as 37 is caused to move any function connected therewith 100 from the normal to the reverse position, move the bridging contacts 38 and 39 from in contact with the springs 40, 41, 42 and 43 respectively, into contact with springs 44

and 45 and 46 and 47 respectively, whereupon a further rotation of the armature of the rotor, whose commutator is designated by 37, generates a current of electricity by its acquired momentum, which flows through the proper wires to energize the indication magnet 16, which by operating armature 18 causes an actuation of the latch and dog underneath the slide so that the slide, which 10 was stopped at the reverse indication position is released so that it may be moved to the full reverse position.

If, when all of the parts are in the full reverse position, the slide 1 is moved in a direction opposite to the arrow X, to the normal indication position, all of that group of parts designated by A, will return to the position shown, and after so doing, a current will flow through the indication magnet 16, which will release the slide 1, so that it may be moved to the full normal position. When the slide 1 is moved to the reverse indication position, the pivoted member 33 is moved into contact with contact 36, and 25 when the slide 1 is moved to the normal indication position after having been moved to the reverse position, the pivoted member 33 is moved back into contact with contact 35. All of the above briefly outlined operations 30 are thoroughly well understood by those skilled in the art of railway signaling, and are explained in detail in the patents granted to John D. Taylor, hereinbefore mentioned.

35 Heretofore the electromagnets 31 and 32 have been made practically of such low resistance, that they would cause an actuation of pivoted member 33, only when sufficient current flowed through them to cause the 40 armature of the motor to revolve, the commutator of which is designated by 37, and the motor would operate when in series with either 31 or 32. Coils 48, 49, 50 and 51 have heretofore been made of such resistance that 45 they would operate members 38 and 39 by a flow of current much less than that needed to actuate member 33, consequently, a current could flow through coils 31 or 32 in series with 51 and 50 or 48 and 49 respectively 50 which would operate the members 38 and 39 but not operate member 33.

In this embodiment of applicant's invention, the electromagnets 31 and 32 have been so designed, that they will operate the armature of the selector when in series with the pole changer coils 48 and 49 or 50 and 51, but the pole changer bridging members 38 and 39 will not be operated when the coils 48 and 49 or 50 and 51 are in series with 55 electromagnets 31 or 32.

As the value of the current which may thus flow through indication selector magnets 31 and 32 is very much less than that required to cause the armature of the motor to revolve, it is necessary to form an

70 operating circuit for the motor which does not include electromagnets 31 and 32. Applicant's invention provides such a circuit, which is formed at the proper time by the movement of pivoted member 52, which is moved back and forth on its pivot by means of electromagnets 31 and 32 and is held firmly in either extreme position by the over-center throwing device 53, and by current flowing in coils 115 and 116. 75

The complete operation of applicant's device is as follows: the operator grasps the handle of the slide 1 and exerts a pull upon the slide in the direction of the arrow X, which causes the slide to move in the direction of the arrow X and so causes shoulder 7 to contact with the left hand end of latch 13, and causes the right hand end of latch 13 to be moved into the space between shoulders 9 and 10, so that the shoulder 10 will 80 contact with the right hand end of latch 13. In order to positively insure that the right hand end of latch 13 will be in the proper position, the cam 15 is rotated by the projection forming shoulders 10 and 11, and 85 acting upon dog 14, forces the upper arm of the dog 14 under the right hand end of latch 13. When the right hand end of latch 13 rests against the shoulder 10, the slide is at the reverse indication position, and the 90 contact blocks 21 and 22 have moved to a position between springs 27 and 28 and 29 and 30 respectively, and a circuit has been formed as follows: positive terminal of battery 54, wire 55, safety magnet 19, wires 56 and 57, electromagnet 31 of the indication selector, wires 58 and 59, spring 30, contact block 22, spring 29, wires 60 and 61, spring 43, wire 91, electromagnet 51, wire 92, electromagnet 50, wire 93, spring 90, bearing 95 upon metallic strip 87 of the rotatable commutator 86, spring 88, wire 94, binding post 83, wires 84 and 85 to the negative terminal of the battery 54. The resistance of the 100 above traced path would be such that electromagnet 31 would be sufficiently energized to cause both pivoted members 32 and 52 to be moved to the left, so that pivoted member 33 would form a conducting path between contact 34 and 36, and pivoted member 52 would be moved so that the over-centering 105 device would snap it and hold it firmly in the extreme left hand position. Of course when the slide 1 is moved to the reverse indication position, current not only flows through coils 51 and 50 but also through the motor but until pivoted member 52, as explained below, moves to reverse position, no useful current flows through the motor. 110

115 As soon as pivoted member 52 contacted with wire 117 a circuit would be formed as follows: positive terminal of battery 54, wire 55, safety magnet 19, wires 56 and 119, pivoted member 52, wire 117, coil 115, wires 95 and 59, spring 30, contact block 22, spring 120

29, wires 60 and 61, spring 43, bridging contact 39, spring 42, wire 62, binding post 63, wire 64, brush 65, commutator 37 and armature to which it is connected, brush 66, wire 67, binding post 68, wire 69, spring 41, bridging contact 38, spring 40, wire 70, binding post 71, wire 72, field coil 73, wire 74, field coil 75, wire 76, binding post 77, wire 78, field coil 79, wire 80, field coil 81, wire 82, binding post 83, wires 84 and 85, to the negative terminal of the battery. Current flowing in the above traced path causes the armature to which commutator 37 is connected to revolve actuating the function to which it is connected, moving the bridging contacts 38 and 39 into contact with springs 44 and 45 and 46 and 47 respectively, and causing rotatable commutator 86 to revolve, so that springs 88 and 89 will contact with metallic member 87 instead of springs 88 and 90, and the acquired momentum still remaining in the armature, to which commutator 37 is attached, after the function has been actuated, will cause the generation of an indication current for which a complete circuit has been formed by the movement of the bridging contacts 38 and 39 caused by the operation of the motor, the operation of the indication selector, and the contact block 21, which is as follows: armature to which commutator 37 is connected, commutator 37, brush 65, wire 64, binding post 63, wire 62, spring 42, wire 96, spring 45, bridging contact 38, spring 44, wire 97, spring 40, wire 70, binding post 71, wire 72, field coil 73, wire 74, field coil 75, wire 76, binding post 77, wire 78, field coil 79, wire 80, field coil 81, wire 82, binding post 83, wires 84 and 98, indication magnet 16, wire 99, contact 34, pivoted member 33, contact 36, wire 100, spring 28, block 21, spring 27, wires 101 and 102, spring 47, bridging contact 39, spring 46, wire 103, spring 41, wire 69, binding post 68, wire 67, brush 66, and commutator 37 to the other terminal of the armature. The indication current flowing in the above traced path will so energize indication magnet 16, that armature 18 will be raised, causing the rod 17 to strike the dog 14, and so cause the upper arm of the dog to be thrown from under the right hand end of latch 13, so that the slide 1 can be moved to the full reverse position, but in such position no operating current will be flowing in wire 61 to the motor as bridging contact 39 is not in contact with spring 43 and no current will flow through electromagnets 50 and 51 because spring 90 is not in contact with metallic member 87.

In order to return all parts to the normal position as shown in the figure, the operator moves the slide 1 in a direction opposite to the arrow X, thereby causing shoulder 8 to contact with the left hand end of the

latch 13 and move the right hand end into the path of shoulder 9, so as to stop the slide at the normal indication position, and at the same time, the cam 15 by contacting with the projection formed by shoulders 10 and 11, will cause the dog 14 to move into a proper position to hold the right hand end of the latch 13 in the path of the shoulder 9. The movement of the slide 1 to the normal indication position, places block 21 in contact with springs 23 and 24, and block 22 in contact with springs 25 and 26, so that a circuit is formed as follows: positive terminal of battery 54, wire 55, safety magnet 19, wires 56 and 104, electromagnet 32 of the indication selector, wires 105 and 106, spring 26, block 22, spring 25, wires 107 and 102, spring 47, wire 108, electromagnet 49, wire 109, electromagnet 48, wire 110, spring 89, metallic strip 87, spring 88, wire 94, binding post 83, and wires 84 and 85 to the negative terminal of the battery. The resistance of the above traced path is such, that sufficient current flows therein, so that the electromagnet 32 is sufficiently energized, so that it moves pivoted members 33 and 52 to the right hand position as shown in the figure, in which pivoted member 33 forms a conducting path between contacts 34 and 35, and pivoted member 52 is held tightly by means of the over-center throwing device 53.

As soon as pivoted member 52 moves to the position as shown in the drawing a circuit is formed as follows: positive terminal 100 of the battery 54, wire 55, safety magnet 19, wires 56 and 119, pivoted member 52, wire 118, coil 116, wires 111 and 106, spring 26, block 22, spring 25, wires 107 and 102, spring 47, bridging contacts 39, spring 46, wire 103, spring 41, wire 69, binding post 68, wire 67, brush 66, commutator 37, armature to which the commutator is connected to brush 65, wire 64, binding post 63, wire 62, spring 42, wire 96, spring 45, bridging contact 38, spring 44, wire 97, spring 40, wire 70, binding post 71, wire 72, field coil 73, wire 74, field coil 75, wire 76, binding post 77, wire 78, field coil 79, wire 80, field coil 81, wire 82, binding post 83, and wires 84 and 85 to the negative terminal of the battery. Current flowing in the above traced path causes the armature to which commutator 37 is connected to rotate, actuates the function to which it is connected, moves bridging contact 38 into contact with springs 40 and 41 and bridging contact 39 into contact with springs 42 and 43 and causes rotatable commutator 86 to rotate, so that springs 88 and 90 make contact with metallic strip 87 of commutator 86, and the armature of the motor by reason of its acquired momentum, after the function is operated, causes the generation of a current, which flows in a circuit as follows: commu-

tator 37, brush 66, wire 67, binding post 68, wire 69, spring 41, bridging contact 38, spring 40, wire 70, binding post 71, wire 72, field coil 73, wire 74, field coil 75, wire 76, binding post 77, wire 78, field coil 79, wire 80, field coil 81, wire 82, binding post 83, wires 84 and 98, indication magnet 16, wire 99, contact 34, pivoted member 33, contact 35, wire 112, spring 24, block 21, spring 23, 10 wires 113 and 61, spring 43, bridging contact 39, spring 42, wire 62, binding post 63, wire 64, brush 65 and commutator 37 to the other terminal of the armature. The current which flows in the above traced path 15 energizes the indication magnet 16, causes the armature 18 bearing the rod 17 to be raised, thus striking dog 14 and forcing its upper arm from beneath the right hand end of latch 13, so that shoulder 9 may pass the 20 right hand end of the latch, so that the slide 1 may be placed in the full normal position, after which all of the parts will be in the position as shown by the figure.

Although applicant has illustrated coils of 25 wire 115 and 116 wound on electromagnets 31 and 32, through which the operating current for the motor and pole changer flows, it is to be understood that such construction is not absolutely necessary. Coil 115 is 30 merely part of the circuit including wire 95, and coil 116 merely part of the circuit including wire 111, but neither coil has any power to actually start the movement of armatures 52 and 33, they merely have a 35 circuit completed through them by the completion of the movement of armature 52, so that they merely act to hold the armature in the moved position after being moved thereto, so as to reduce the resistance of the 40 contact between armature 52 and either contact point 117 or 118. Such construction merely assists the spring 53 to retain member 52 in the thrown position, when operating current is flowing. Applicant 45 may use both spring 53 and coils 115 and 116 or use one means only to hold member 52 in the thrown position. Although applicant has illustrated two armatures, as 52 and 33, it is not to be inferred 50 that two are necessary, for no reason exists why one armature may not be made to perform the circuit closing functions of both.

Several points not necessary to explain in 55 describing the complete normal operations should be observed, they are: 1. Although current flows through the pole changer coils 48 and 49 and 50 and 51 when the slide 1 is moved either from the normal position to the reverse indication position or from the 60 reverse position to the normal indication position, as such current must first flow through either electromagnets 31 or 32 it is not of sufficient value to cause a movement of bridging contacts 38 and 39, but it is not 65 until pivoted member 52 is thrown and a

shunt formed about electro-magnets 31 or 32 that the current flowing to said coils 48 and 49 or 50 and 51 reaches such a value as to sufficiently energize the coils to cause a movement of members 38 and 39 if the 70 switch operating mechanism has been partly moved to release these contacts: 2. Although a movement of the slide 1 to either indication position forms a circuit in which a selector coil as 31 or 32 and the motor are 75 in series, sufficient current to operate the motor cannot flow until member 52 has first been thrown, thereby shunting either coil 31 or 32, thus reducing the resistance of the path: 3. That although the circuit which 80 is formed having a selector coil and the motor in series does not allow the motor to operate it will allow the selector to operate, but such circuit may be considered as an accidental circuit as far as normal operation 85 is concerned.

One advantage of applicant's invention can be most readily seen by a concrete illustration. If the slide 1 is moved to the reverse indication position, a current should 90 then flow along through selector coil 31 and the wire 61 and through wire 91 and electro-magnets 51 and 50, wire 93, spring 90, metallic strip 87, spring 88, wire 94, binding post 83, and wires 84 and 85 to the negative 95 terminal of the battery. The current flowing in the above traced path would cause member 52 to shunt coil 31 and then the current would flow in the same path as above described with the exception of coil 31 and is intended to sufficiently energize electro-magnets 51 and 50, so that bridging contacts 38 and 39 will be held in the position as 100 shown, until the function to which the motor is connected has made a complete movement, 105 whereupon the bridging contacts 38 and 39 should be mechanically moved into contact with springs 44 and 45 and 46 and 47 during the latter part of the lock movement as fully shown, described and claimed in Patent 110 #800,246 hereinbefore mentioned. As also fully explained in Patent #800,246, the bridging contacts 38 and 39 are free from the mechanical actuating means during all of the actual operation of the function, except the very first and the last part of its lock movement, so that during all of the time they are free, they may be moved back and forth by alternate energization of electromagnets 50 and 51 and 48 and 49. As 115 fully explained in Patent #800,246, this is for the purpose of allowing an operator to move a function, such as a railway switch, which will not complete its movement, back and forth, so that any obstacle between the switch point and the stock rail may thereby perhaps become crushed, thus allowing the operator to actually move the switch, without being obliged to leave the operating tower, from which such switches are usually 120 125 130

operated, and go out upon the ground and actually remove the obstruction. It is also to be observed, that as fully explained in Patent #800,246, the bridging contacts 38 and 39 remain in contact with the springs 40 and 41 and 42 and 43 until the switch or other function has actually completed its movement, and been almost locked, whereupon the bridging contacts 38 and 39 move to the reverse position, and then, and not until then, complete the indication circuit heretofore traced. The object of causing the bridging contacts 38 and 39 to so operate is to prevent any possibility of an indication being received before the switch or other function has been actually moved to the full reverse position and locked therein.

In order that the advantage of applicant's mode of construction may be the more clearly understood, it will be pointed out how a given accident to the old and well known construction, in accordance with the Taylor patents hereinbefore mentioned, allows the slide 1 to be placed at reverse with the function controlled thereby in an intermediate position, and then it will be pointed out how applicant's construction prevents the possibility of the slide 1 being at reverse position when the function controlled thereby is at an intermediate position. First consider the old and well known construction, that is, a system constructed in accordance with the patents hereinbefore mentioned, that is a system in which the indication selector has only one pivoted member as 33 actuated thereby, as in Patent 832,175 hereinbefore mentioned, and in which the electromagnet as 31 is of such resistance that in order to operate it a current has to flow therethrough sufficient to operate the motor such as that of which the commutator is 37, and in which coils such as 51 and 50 and 49 and 48 will operate the movable bridging contacts 38 and 39 when the coils are in series with coils such as 31 or 32 respectively upon a flow of current very much less than that required to operatively energize the coils such as 31 or 32. Assume that in such a system a wire such as 91 becomes accidentally broken as at 114. In that case there is the possibility of an improper operation whereby a slide such as 1 may be placed in a position out of correspondence with the function controlled by the motor controlled by the slide. This is best understood by following the operation of the parts of such a system when such an accident as has been mentioned has happened. As the schematic representation of such a system does not differ from the figure of drawing except that the parts 52, 118, 111, 116, 95, 115, and 117 would not be present, such figure will be taken as an example of such a system and it will be assumed that the mentioned parts are missing. In such a system if slide 1 is

moved to the reverse indication position, then a current would flow through the electromagnet 31 moving the pivoted member 33 to the left and causing an actuation of the motor and of the function.

Assume that before the switch or function has completed its movement, the operator returns the slide 1 to the normal indication position, then current will flow through the electromagnet 32, wires 105 and 106, spring 26, block 22, spring 25, wires 107 and 102, spring 47, wire 108, electromagnet 49, wire 109, electromagnet 48, wire 110, spring 89, metallic strip 87, which by the partial movement of the function has been placed in position to contact with the springs 88 and 89, thence by spring 88, wire 94, binding post 83 and wires 84 and 85 back to the battery. Remembering that it is assumed that the system now being considered does not embody this invention, it can be seen from a consideration of the Patent No. 800,246, hereinbefore mentioned, that the current flowing in the above traced path would energize the electromagnet 48 and 49, even with the electromagnet 32 in series therewith, sufficiently to cause the bridging members 38 and 39 to be set in motion toward the springs 44, 45, 46, and 47, thereby cutting off the supply of operating current to the motor. The indication selector electromagnet 32, however, still remembering that the system under consideration does not embody this invention, would not be energized sufficiently to operate its armature 33, since the operating current is cut off from the motor at the pole changer. At this time, while the motor is rotating idly by virtue of its acquired momentum, if the operator makes a quick movement of the slide 1 to its reverse indication position, so that the block 21 operated by said slide is brought into contact with the springs 27 and 28 at or about the same time that the bridging members 38 and 39 complete their movement and make contact with the springs 44, 45, 46, and 47, a false indication will be received, since the motor is rotating and is capable of generating the indication current, and since there is an indication circuit, in which current generated by the rotation of the armature to which commutator 37 is connected, could flow as follows: commutator 37, brush 65, wire 64, binding post 63, wire 62, spring 42, wire 96, spring 45, bridging contact 38, spring 44, wire 97, wire 70, binding post 71, wire 72, field 73, wire 74, field 75, wire 76, binding post 77, wire 78, field 79, wire 80, field 81, wire 82, binding post 83, wires 84 and 98, indication magnet 16, wire 99, contact 34, pivoted member 33, contact 36, wire 100, spring 28, block 21, spring 27, wires 101 and 102 and spring 47, bridging contact 39, spring 46, wire 103, spring 41, wire 69, binding post 68, wire 67, brush 66, commu-

tator 37 and to the other terminal of the armature. The current flowing in the above traced path would energize the indication magnet 16, cause the armature 18 bearing 5 the rod 17 to be raised, force the dog 14 from beneath the right hand end of latch 13 and allow the right hand end of latch 13 to move out of the path of the shoulder 10 of the slide 1, so that the slide 1 could be moved 10 to the full reverse position, and the switch or function would be in the mid-position, as the operating current would be cut off before the switch completed its movement at members 38 and 39, so that other slides dependent upon the complete movement of 15 slide 1, through the mechanical locking controlled by members 6, would be released and could be operated to cause the function connected therewith to be actuated, and under such conditions, if the other slide dependent 20 upon the complete movement of the slide 1 were a signal lever, the signal could be cleared with the switch, over which it controls train movements, in the mid-position. 25 Although the above operation as described appears very complex, and as actually performed would require a very skilled operator and all of the movements would have to be very nicely timed, as such a possibility exists, it should be remedied, because the railway signal art today demands of a device not only that it shall operate perfectly and safely under normal conditions, but that it shall operate safely under abnormal 30 conditions. It should be also noted that, in addition to skilful operation, it is necessary that the wire 91 be broken in order to obtain the result above described, since if the wire 91 was intact when the slide was returned to 35 the reverse indication position after having been moved to the normal indication position to shift the bridging contacts 38 and 39, a circuit would have been formed through electromagnets 50 and 51 which would have 40 overcome the impulse given to the bridging contacts 38 and 39 and would have returned them to the position shown in the drawing, thus preventing the completion of an indication circuit. 45 In the construction disclosed in this application, even if the wire 91 were broken, the skilful manipulation hereinbefore described would not result in a false indication, for, if the slide 1 were moved to the reverse indication 50 position, pivoted member 33 would be moved to the left before any movement of the pole changer members 38 and 39 took place, for applicant has so designed the electromagnets 31 and 32, that the pole changer cannot operate when in series therewith, but it is necessary for both pivoted members 33 and 52 to first move so that one, to-wit, 52, can shunt an electromagnet coil 55 as 31 before the path for current through the motor or the pole changer is of suffi-

ciently low resistance to enable sufficient current to flow therethrough to operate the pole changer or the motor. If the wire 91 were broken, and the slide 1 were moved to the normal indication position after having 70 been moved to the reverse position, the pivoted member 33 would move before the bridging members 38 and 39, for in applicant's invention the value of current needed to operate members 38 and 39 is greater 75 than that needed to move member 33, and that value of current is much less than that required to operate the motor, so the pivoted member 33 would first move to the right as shown in the figure than the bridging contacts 38 and 39 would move to the left. Consequently, although the motor were rotating, and the bridging members 38 and 39 were moving toward contact between springs 44 and 45 and 46 and 47, and although the slide 1 were then quickly moved to the reverse indication position, so that block 21 made contact between springs 27 and 28, an indication circuit would not be formed, consequently because members 38 90 and 39 would be in a position reverse to that shown, and wire 91 being broken, no current could flow through wire 61 to common 84, so coil 31 could not be energized to move arm 33 to the reverse position, the continuity 95 of the indication circuit would be broken between contact 36 and contact 34, therefore the slide could not be moved to the full reverse position, thus releasing the locking of conflicting slides. 100

Although I have particularly described the construction of one physical embodiment of my invention, and explained the operation and principle thereof; nevertheless, I desire to have it understood that the form 105 selected is merely illustrative, but does not exhaust the possible physical embodiments of the idea of means underlying my invention.

What I claim as new and desire to secure 110 by Letters Patent of the United States, is:

1. In an electric interlocking system, a motor, a pole changer, an indication selector having an armature, a circuit controller, means to operate the circuit controller, an indication device controlling said means, a source of electricity, electrical conductors connecting the motor, pole changer, indication selector, and indication device with the source of current and with each other, the motor, indication selector and pole changer being of such relative resistance, that the pole changer will not operate in series with the indication selector and the motor will not operate in series with the indication selector, and means governed by the indication selector to establish a shunt around the indication selector. 120

2. In an electric interlocking system, in combination: a motor having an armature; 130

operating circuits for said motor; a pole changer for changing the connection between the armature of said motor and said operating circuits; electromagnetic means 5 for shifting said pole changer; indication mechanism; indication circuits for said mechanism; a circuit controller for controlling said indication circuits; electromagnets for controlling said circuit controller; series circuits including said electromagnetic means for operating said pole changer and the corresponding electromagnets; an armature governed by said electromagnets; and a partial shunt circuit for each of said 10 electromagnets controlled by said armature. 15

3. In an electric interlocking system, in combination: an electrically operated function; manually operable circuit controlling means for governing the movements of said 20 function; indication mechanism for said circuit controlling means; an indication circuit for said indication mechanism, said indication circuit being controlled by said circuit controlling means; a circuit controller 25 at the function operated thereby and included in said indication circuit; a second circuit controller included in said indication circuit; and means for operating said second circuit controller and said first circuit controller successively and in the order named.

4. In an electric interlocking system, in combination: an electrically operated function; indication mechanism; an indication 35 circuit for said indication mechanism; electrically operated means associated with said function for controlling said indication circuit; a circuit controller included in said indication circuit; electromagnets for operating said circuit controller; circuits each 40 including in series one of said electrically operated means and the corresponding electromagnet; the resistance of each of said last-mentioned series circuits normally limiting the flow of current therein to an 45 amount less than is necessary for operating said electrically operated means, without preventing the operation of said circuit controller by said electromagnet; and means 50 operated by each of said electromagnets for reducing the corresponding resistance.

5. In an electric interlocking system, in combination: an electrically operated func-

tion; indication mechanism, an indication circuit for said indication mechanism; electrically operated means associated with said function for controlling said indication circuit; a circuit controller included in said indication circuit; electromagnets for operating said circuit controller; circuits each including in series one of said electrically operated means and the corresponding electromagnet, the resistance of each of said electromagnets being such as to limit the flow of current in the corresponding last-mentioned 65 series circuit to an amount less than is necessary for operating said electrically operated means, without preventing the operation of said circuit controller by said electromagnet; and means selectively governed 70 by said electromagnets for establishing a shunt around the electromagnet which is energized.

6. In an electric interlocking system, in combination: a function; a motor having an 75 armature for operating said function; a source of current; operating wires for said motor; a manually operable circuit controlling lever for controlling the connection between said operating wires and said source 80 of current; a pole changer for controlling the connection between said operating wires and the armature of said motor; electromagnets for operating said pole changer; indication mechanism for said lever; indication 85 circuits for said indication mechanism controlled by said lever and by said pole changer; a circuit controller for selectively controlling the connection between said indication circuits and said lever; other electromagnets for operating said circuit controller; circuits each including in series one of said other electromagnets and the corresponding one of said first-mentioned electromagnets of said pole changer, the resistance 95 of said other electromagnets being such that said pole changer electromagnets will not operate said pole changer although said other electromagnets can operate said circuit controller; and a shunt for each of said electromagnets controlled by said circuit controller. 100
